UNITED STATES PATENT OFFICE.

GEORGE F. KRIEGER, OF CHICAGO, ILLINOIS, ASSIGNOR OF ONE-THIRD TO
ADIE B. HORN, OF SAME PLACE.

HAND-PRESS FOR MAKING METAL CAPS.

SPECIFICATION forming part of Letters Patent No. 650,467, dated May 29, 1900.

Application filed February 23, 1900. Serial No. 6,252. (No model.)

To all whom it may concern:

Be it known that I, GEORGE F. KRIEGER, a citizen of the United States of America, and a resident of Chicago, in the county of Cook and State of Illinois, have invented certain new and useful Improvements in Hand-Presses for Making Metal Caps, of which the following is a specification.

My invention relates particularly to means for making blank caps from which dental cap-crowns are afterward formed.

The main object of my invention is to provide a device of simple and comparatively inexpensive construction which may be conveniently used by dentists in making dental cap-crowns.

The further objects of the different parts with which I put my invention into practice will be understood from the following description, with reference to the accompanying drawings, in which—

Figure 1 is a vertical section of the lower part of a device constructed according to my invention, showing same held by the jaws 25 of a vise and illustrating the position of the parts preparatory to forming a metal cap. Fig. 2 is the same view with the upper parts attached, showing the different steps in the process of forming the cap. Fig. 3 is the same view, showing the position of the parts when the cap is completed and having the base of the device turned at right angles to its former position to show the lugs whereby said base is secured in the vise. Fig. 4 is a section of the cap after the first step in the process of making same. Fig. 5 is a section of the complete cap. Fig. 6 is a plan of a wrench used in connection with the device shown in the other figures.

The device shown consists of a hollow base, a pair of cones fitting in the same, a sleeve threaded upon said base, a screw-cap threaded upon said sleeve, a screw threaded in said cap, and a plunger loosely seated at the lower end of said screw.

The base 1 is exteriorly threaded at 2 and has a shoulder 3 for supporting the cone 4. Said cone has a seat 25 with an annular groove 5 therein for receiving the disk 6, from which the cap is afterward formed. The cone 7 is vertically slidable in the base 1. Each

of said cones has a central aperture of slightly greater diameter than the plunger 8. The plunger 8 is vertically slidable in the sleeve 9. Said sleeve has a shoulder 25, which rests 55 on the cone 7 when the sleeve 9 is screwed down for the purpose of pressing the cone 7 upon the disk 6. The cap 10 is threaded upon the upper end of the sleeve 9 and has a central threaded aperture for receiving the 60 screw 11. Said screw has a circular aperture 12 at its lower end for receiving the pin 13 of the plunger 8. The head 14 of the screw 11 is rigid thereon and has an aperture for receiving the rod 15. Said rod is tightened in said aperture by the set-screw 16. The outer end of the rod is bent upwardly at 17, serving as a handle for the operator in turning the screw 11. The base 1 is provided with lugs 18, whereby the same may be 70 secured in the vise-jaws 19. The sleeve 9 is provided with an aperture 20, serving as a seat for the pin 21 of the wrench 22. The screw-head 10 is provided with a similar aperture 23 for receiving the pin 24 of said 75 wrench.

The cones 4 and 7 are made removable, so that other cones with central apertures of a different size may be substituted for making caps of different sizes. A further advantage 80 of using the cone 4 instead of making the seat 25 integral with the base 1 is that said cone 4 may be stamped out of sheet-steel and readily tempered.

The operation of the device is as follows: 85 A disk 6 is first seated in the groove 5 of the cone 4 in the position shown in Fig. 1. The cone 7 is then placed upon the disk 6, and the sleeve 9 is screwed down upon same to the position shown in Fig. 1. The wrench is then 90 applied by inserting the pin 21 in the aperture 20. The operator then screws the sleeve down by means of said wrench until the cone 7 is pressed down upon the disk 6 to its lower limit, as shown in Fig. 2. He will then insert 95 the plunger 8, allowing same to drop to the position shown in Fig. 2. The screw-cap 10 will then be screwed down upon the sleeve 9, and the screw 11 will be turned in said cap until the same engages the plunger 8, as 100 shown in Fig. 2. The operator will now continue to turn said screw by means of the rod

15 until the plunger forces the disk into the form and position shown in Fig. 3. Said plunger and cap will now drop through the lower end of the base 1. The screw-cap 10 5 and screw 11 may be first attached together in about the relation shown in Fig. 2 before said screw-cap is attached to the sleeve 9. The operator may then use the wrench 22 in tightening said screw-cap upon the sleeve 9, 10 and thus bring the screw 11 down upon the plunger 8.

It will be understood that minor details of the device shown may be altered in numerous ways without departing from the spirit 15 of my invention. I therefore do not confine myself to such details, except as hereinafter limited in the claims.

What I claim as my invention, and desire to secure by Letters Patent, is—

20 1. In a press for making metal caps, the combination of a hollow base, having a conical apertured seat therein, an apertured cone vertically slidable in said base and formed to register with said seat, a member engaging 25 said base for forcing said cone upon the seat and locking same thereon, and a plunger vertically slidable through the apertures in said cone and seat, substantially as described.

2. In a press for making metal caps, the 30 combination of a hollow base, having a conical apertured seat therein, an apertured cone vertically slidable in said base and formed to register with said seat, a sleeve threaded upon said base and having a shoulder for bearing 35 upon said cone, and a plunger vertically slid- able through the apertures in said cone and seat, substantially as described.

3. In a press for making metal caps, the 40 combination of a hollow base, having a conical apertured seat therein, an apertured cone vertically slidable in said base and formed to register with said seat, a sleeve threaded upon said base and having a shoulder for bearing upon said cone, a screw threaded in 45 said sleeve, and a plunger vertically slidable

through the apertures in said cone and seat, adapted to be forced downward by said screw, substantially as described.

4. In a press for making metal caps, the combination of a hollow base, having a conical apertured seat therein, an apertured cone vertically slidable in said base and formed to register with said seat, a sleeve threaded upon said base and having a shoulder for bearing upon said cone, a screw-cap threaded upon 50 said sleeve and having a threaded aperture in its top, a screw seated in said threaded aperture, and a plunger vertically slidable through the apertures in said cone and conical seat and adapted to be forced downwardly 55 by said screw, substantially as described.

5. In a press for making metal caps, the combination of a hollow base, having a conical apertured seat therein, with an annular groove in the face of said seat and surround- 60 ing the aperture therein, an apertured cone vertically slidable in said base and formed to register with said seat, a member engaging said base for forcing said cone upon the seat and locking same thereon, and a plunger ver- 65 tically slidable through the apertures in said cone and seat, substantially as described.

6. In a press for making metal caps, the combination of a hollow base, an apertured member removably seated in said base and 70 having a conical apertured seat therein, an apertured cone vertically slidable in and re- 75 movable from the base and formed to regis- ter with said seat, a member engaging said base for forcing said cone upon the seat and locking same thereon, and a plunger verti- 80 cally slidable through the apertures in said cone and seat, substantially as described.

Signed by me at Chicago, Illinois, this 21st day of February, 1900.

GEORGE F. KRIEGER.
